UNITED STATES PATENT OFFICE.

NICHOLAS HOHFELT, OF DETROIT, MICHIGAN, ASSIGNOR OF ONE-HALF TO JAMES P. McHUGH, OF DETROIT, MICHIGAN.

PACKAGE.

1,186,194.

Specification of Letters Patent.

Patented June 6, 1916.

Application filed April 27, 1914. Serial No. 834,756.

To all whom it may concern:

Be it known that I, NICHOLAS HOHFELT, a citizen of the United States of America, residing at Detroit, in the county of Wayne 5 and State of Michigan, have invented certain new and useful Improvements in Packages, of which the following is a specification, reference being had therein to the accompanying drawings.

10 My invention relates to packages, and more particularly to a package containing cigars.

The invention resides in certain constructions, arrangements and combinations of 15 parts as will more fully hereinafter appear.

In the drawings,—Figure 1 is a perspective view of a package embodying the invention; and Fig. 2 is a similar view showing the package arranged to display the 20 cigars thereof.

Cigar boxes now in general use have the cover hinged at one edge to the body of the box and have affixed to the inner face of the cover an enlargement of the label, trademark 25 or other trade symbol of the cigars. In arranging cigar boxes in a show-case it is very desirable to have the cigars in the boxes clearly displayed and also to conspicuously exhibit the label affixed to the inner face of 30 the cover, so that the brand of the cigars may be readily detected by looking at the label upon the cover, while the type of cigars within the box can be ascertained. However, with such a type of cigar box, in order 35 to properly display the cigars, it is necessary to completely open the cover. This is objectionable since the cigar boxes are arranged in the show-case so as to abut against the adjacent boxes, in order that the boxes 40 may occupy the minimum space, and when so arranged the open cover of one box shields from observation the box in rear thereof.

By my invention I have provided a package by which not only may the trade symbol 45 upon the inner face of the cover be conspicuously exhibited but also the cigars of the package properly displayed, and these results accomplished while permitting the boxes to occupy the minimum amount of 50 space in the show-case.

My improved package comprises a box A and cigars B therein. The box A is composed of a body portion C and a cover. The latter instead of being formed of a single rigid member and hinged to one side edge 55 of the box, is formed of a plurality of sections—preferably two, designated by D and E. One of the sections as E is attached to the body of the box and the two sections are hingedly connected together as by hinges F. 60 Preferably the section D is secured to one end of the box as by hinges F'. The hinge connection however, between the two sections and also between one of the sections and the end of the box may be formed in any 65 suitable manner. Preferably the two sections D and E are formed of substantially the same size so that when the section D is turned back, as shown in Fig. 2, it will not project beyond the end of the box. 70

Affixed to the inner face G of the section E and arranged thereupon to be properly displayed when the section E is turned back to the position shown in Fig. 2, is the trade symbol for the cigars of the package, this 75 symbol being herein shown as a label H having thereon the trademark I for the cigars. As shown in Fig. 2, the cigars B are arranged crosswise of the box and, therefore, when the section E is open, a portion of the 80 cigars will be completely displayed.

With my improvement it will be readily apparent that the boxes may be arranged within a show-case to occupy the minimum amount of space, and that when one section 85 of the cover is open, not only will the trade symbol affixed to the inner face thereof be conspicuously displayed and a portion of the cigars completely exhibited, but also the cover will not shield an adjacent package 90 from view.

What I claim as my invention is:

A package for cigars, comprising a box composed of a body portion, and a cover formed in two sections of practically the 95 same size, one of said sections being connected to the body portion and the other section being hingedly connected with the first-mentioned section to permit of being turned back upon the first-mentioned section, the 100

cigars within the box arranged crosswise thereof, and a trade symbol upon the inner face of said second section whereby upon the opening of said second section a portion of 5 said cigars are completely displayed and said trade symbol upon the inner face of the last-mentioned section exhibited.

In testimony whereof I affix my signature in presence of two witnesses.

NICHOLAS HOHFELT.
